CLAIM

The ornamental design for a tiered utility rack, as shown and described.

DESCRIPTION

FIG. 1 is a front perspective view of a tiered utility rack; FIG. 2 is a front elevation view thereof, the rear elevation view being a mirror image thereof;

FIG. 3 is a left side elevation view thereof, the right side elevation view being a mirror image thereof; and, FIG. 4 is a top plan view thereof, the bottom plan view being a mirror image thereof.

The broken lines shown in the drawings depict portions of the tiered utility rack that form no part of the claimed design. The break lines shown in FIGS. 1, 2, and 3 are not part of the claimed design and represent that no particular length is claimed.
